UNITED STATES PATENT OFFICE.

JOHN PHIPPS, OF PHILADELPHIA, PA., ASSIGNOR TO THE MARTIN LANDENBERGER MANUFACTURING COMPANY, OF SAME PLACE.

DESIGN FOR A STOCKING.

Specification forming part of Design No. **11,163**, dated April 15, 1879; application filed March 17, 1879
[Term of patent 3½ years.]

To all whom it may concern:

Be it known that I, JOHN PHIPPS, of Philadelphia, Pennsylvania, have invented a new and original Design for a Stocking, of which the following is a specification.

My design for a stocking is fully shown in the accompanying drawing, which represents a side view of the stocking.

The stocking has a foot, A, and top B of uniform color, and between these two portions intervenes a broad stripe, D, which is crossed by narrow vertical bars or stripes *a* and narrow horizontal bars or stripes *b*, forming a plaid.

Irrespective of the colors employed, I claim—
1. The design for a stocking, comprising the

foot A, top B, and intervening stripe D, with narrow vertical bars or stripes *a*, all substantially as described and shown.

2. The design for a stocking, comprising the foot A, top B, and intervening stripe D, with narrow vertical bars or stripes *a* and horizontal bars or stripes *b*, all substantially as described and shown.

In testimony whereof I have signed my name to this specification in the presence of two subscribing witnesses.

JOHN PHIPPS.
